UNITED STATES PATENT OFFICE

2,541,946

SOUND WAVE DIFFUSER

Lawrence M. Stark, Alexandria, Va.

Application June 1, 1948, Serial No. 30,406

7 Claims. (Cl. 181—31)

1

This invention relates generally to the art of reproducing recorded and radio transmitted sound and it is a particular object of the invention to provide a means for generally improving the reproduction of sound from loud speakers, such as are usually associated with full frequency range radios, phonographs and the like.

It is well known that the sound emanating from the diaphragm of a reproducer consists of many different audible frequencies, the highest of which are produced by the portion of the diaphragm nearest to the center and the lowest by the portion farthest from the center. It is also well known that the highest of the frequencies are transmitted much in the form of a beam and in high quality radios and phonographs affording full range reproduction, audio-frequency vibrations extending to 15,000 cycles per second are often encountered. It is in the higher frequency portion of the audible spectrum, that is, from 4,000 to 15,000 cycles per second, that this beam becomes very pronounced. A listener located in front of such a reproducer will receive the high frequency component of speech or music with undue emphasis, while one located at the side of such reproducer will not receive this high frequency component in sufficient emphasis.

It is a further object of the present invention to provide a device which may be either incorporated into the loud speaker assembly as a unit by the manufacturer for use with radios, phonographs and the like or for addition to and employment with the loud speaker, which will effect a dispersion and diffusion of a large proportion of the high frequency vibrations in such a manner that a listener positioned to one side of the reproducer as well as in front thereof will receive the proper proportion of the high and low frequency vibrations with the proper emphasis for the fullest enjoyment of the same.

Another object of the invention is to provide a device designed to be disposed in front of the cone of a loud speaker, which is so constructed that a large proportion of the axially directed beam of high frequency vibrations will not only be deflected laterally but will be fanned out so as to be spread to the fullest extent through a wide area.

Still another object of the invention is to provide a device of the character stated wherein an auxiliary means is provided for deflecting a portion of the high frequency vibrations not dispersed by the preceding means whereby a second and independent band or path of deflected vibrations is produced.

2

Still another object of the invention is to provide a device of the character stated which is designed to permit the proper amount of high frequency vibrations to be deflected and diffused and at the same time permit a proportion of the high frequency vibrations to pass through undeflected and undiffused.

Still another object of the invention is to provide an efficient and inexpensive diffusing device for producing the results stated, which is readily adaptable to many types and sizes of loud speakers.

The invention will be best understood from a consideration of the following detailed description taken in connection with the accompanying drawings forming a part of the specification, with the understanding, however, that the invention is not to be limited to the exact details of construction shown and described since obvious modifications will occur to a person skilled in the art.

In the drawings:

Figure 1 is a view in section in an axially extending plane through a device constructed in accordance with the present invention, showing the same in applied position between the cone of a loud speaker unit and a mounting panel.

Figure 2 is a view on an enlarged scale partly in elevation and partly in section showing in part the manner in which the high frequency vibrations are spread and diffused.

Figure 3 is a view in elevation of the outer end of the device.

Figure 4 is a view in elevation of the inner end of the device.

Figure 5 is a view showing in separated relation and in side elevation the inner and outer cones, the same being on an enlarged scale.

Figure 6 is a view in perspective of the device as seen from the front or outer end.

Figure 7 is a sectional view taken substantially on the line 7—7 of Figure 1.

Referring now more particularly to the drawings, the reference character S generally designates a more or less diagrammatically illustrated loud speaker unit such as forms a part of every radio receiving set and record player, such units having at the forward end of the cone, the encircling mounting flange S.

Such reproducers are commonly mounted upon a baffle board forming a part of a housing cabinet and a portion of such board is here illustrated and designated B, the same having an opening B' therein for the passage therethrough of the sound waves from the speaker.

The diffuser device of the present invention is interposed between the speaker cone and the baffle board as shown in Figure 1 and such device is generally designated D.

In accordance with the present invention the diffuser comprises a cylindrical body 10 having formed integrally therewith the encircling end flanges 11. As shown in Figure 1 one of these flanges is positioned against the rear side of the baffle board B and is secured thereto in a suitable manner by securing elements 12 while the other flange has positioned thereagainst the mounting flange S' of the speaker and these flanges are joined together by securing elements 13 of suitable character.

Supported on the axial center of the cylinder 10 which provides a sound wave guiding passage from the speaker cone to the baffle board opening B', is a diffusing cone which is generally designated 14 and which may be formed of metal or any other suitable material as also may be the cylindrical housing body 10. This diffusing cone 14 is maintained in proper position or coaxially in the cylindrical housing body 10, by means of the radial mounting arms or struts 15 which extend from the base portion of the cone radially outwardly and connect with the wall of the cylindrical body 10, and the rear or inner end arms 16 which are here shown as two in number and which extend radially from the apex portion of the cone outwardly for connection with the body 10.

As is readily seen in Figure 1 the diffusion cone 14 which is actually in the form of a frustum and which is both hollow and open at its base and apex ends, has the apex end disposed toward the speaker cone, and is, of course, coaxial therewith.

The diffusion cone 14 is constructed with its wall of longitudinally arcuate or convex form and the surface curvature is of a prescribed or definite radius depending upon the diameter of the speaker cone.

Formed through and extending longitudinally of the cone 14 are slots 17 which extend through very nearly the entire length of the cone. Between these long slots or full cone length slots 17 are shorter longitudinally extending slots 18 which, in addition to being shorter than the slots 17 are of smaller width. These short slots 18 are disposed at the small end of the cone and extend only through a portion of the length thereof, preferably approximately through one fourth the length of the cone. Preferably there are eight of the long slots and eight of the shorter slots, the shorter slots being positioned centrally between the long slots and all of the slots being equidistantly spaced around the cone.

Disposed within and concentric with the cone 14, is the smaller inner cone which is generally designated 19 and which is open at its apex and base ends as is clearly shown in Figures 1 and 2. This smaller inner cone has its wall straight throughout as opposed to the outward curvature or bow longitudinally of the wall of the larger outer cone.

The outer cone is positioned with the plane of its base flush with the plane of the forward end of the cylinder 10 and the smaller inner cone 12 is also positioned to have the plane of its base in a common plane with the base of the larger cone and the end of the cylinder as is also clearly shown in Figures 1 and 2.

It will also be readily seen that the diameter of the base of the smaller cone is materially

less than the diameter of the base of the larger cone and the smaller cone is maintained in coaxial relation with the larger cone and the cylinder, by means of the three radial arms 20 which connect the base portion of the small cone with the base portion of the large cone as best seen in Figure 6.

The smaller cone 19 which has its apex portion cut off and which accordingly is actually a frustum of a cone the same as the larger cone 14, has formed through the wall thereof the eight longitudinally extending slots 21. Eight slots are here specified for the smaller cone because this is the number of long slots formed in the larger cone 14 and the cones are relatively positioned so that the slots of the smaller inner cone will be in the radial planes of the long slots of the larger cone as is clearly shown in Figure 7. This arrangement permits a desired proportion of the sound waves to pass directly through the two cones and in a straight line outwardly from the speaker.

In Figure 2 the broken lines designated 22 represent one half of all of the high frequency waves passing from the reproducer or speaker S and entering the high frequency diffuser device of the present invention. From point 23 to point 24 the proper portion of the highest frequencies striking the surface 14, is deflected. Another portion passes through the short slots 18 and is deflected by the surface of the smaller inner cone 19 approximately from point 25 to point 26. Still another portion passes through both cones undeflected by reason of the radial alignment of the slots 17 and 21.

As a result of placing the slots 17 and 21 in line with one another the short slots 18 will be in a position, relative to the small cone 19, as between slots 21 of the small cone and the effective lateral area covered by slots 18 will be approximately from point 25 to point 26 on the smaller cone 19. Some deviation from the foregoing is permissible as regards the number of longitudinal slots, their size and placement. However it has been found that the best overall results are obtained when the following specifications are employed. In giving these specifications however, it is to be understood that there is no intention of limiting the invention to the same.

In a construction where the overall diameter of the cylinder is approximately fifteen inches including the flanges 11 the diffusing cone 14 will be approximately four and three-quarter inches in diameter and five inches long. The diffusing cone 19 is approximately two and three-eighths inches in diameter and two and three-quarter inches long. The smaller end opening of the larger cone 14 is approximately one inch in diameter while the diameter of the small opening of the smaller cone 19 will be approximately five-sixteenths of an inch in diameter.

With the dimensions given the curve of the wall of the larger cone 14 will have a radius of approximately nineteen inches and this radius would be correspondingly reduced or decreased in diffusers of smaller design.

The width of the slots in the cones is made in accordance with the amount of the radiations which it is desired to have pass directly through the diffuser or in other words in accordance with the amount to be deflected. A desirable dimension for the slots in a diffuser of the approximate dimensions above set forth is one-fifth of an inch width for the slots 17 and approximately one-eighth of an inch width for the shorter slots 75

18 located therebetween. For the smaller cone 19 the width of the slots is the same as for the slots 17 of the larger cone. With slots of the sizes given and with the number shown it is found that approximately eighth-ninths of all of the high frequency speaker radiations are deflected and dispersed while one-ninth of the same pass through the cones undeflected. Accordingly the design herewith given follows this pattern:

It will be readily apparent from the foregoing that since the angle of the deflected wave is approximately the same as that of the incident wave and since the angle of incidence is progressively changing from the apex to the base of the cone 14, it follows that the angles of the deflected vibrations from the surface of this cone 14 are likewise changing as they are followed from the apex to the base of said cone. This results in a much more thorough and complete dispersion of the deflected high frequency sound vibrations than could possibly be obtained through the employment of a deflecting surface without curvature.

In the illustration it will be seen that the length of the cylinder or mounting rim is very nearly as great as the length of the larger cone 14. This construction or arrangement is desirable for the use of the diffuser device with dual speakers employing a coaxially mounted cone "tweeter" within the large cone "woofer."

In the type of coaxial speaker incorporating a compression-type high frequency unit together with a cone-type low frequency unit a shorter or narrower cylinder will be used since there is usually more space within the large speaker to accommodate a greater portion of the larger diffusing cone 14.

I claim:

1. The combination of a loud speaker and a sound wave diffuser unit therefor, said unit comprising a hollow body open at both ends, means for supporting said body at the front end of said speaker, a hollow frustum of a cone open at both its apex and base ends, means supporting the cone within said body coaxial alignment with the speaker cone with the open apex end directed into the speaker cone, said first cone having a longitudinally convexed surface covering a circular area around the axis of the cones of a materially smaller radius than the radius of the speaker cone to have the major portion of the waves making up the high frequency beam impinge against said surface, and said first cone having longitudinal slot openings therein for the passage of a portion of said beam therethrough.

2. The combination with a loud speaker as set forth in claim 1, with a second and smaller hollow frustum of a cone open at its apex and base ends, supported coaxially with and within the first mentioned cone, the base ends of the two hollow cones being in a common plane perpendicular to the wave beam.

3. The combination with a loud speaker as set forth in claim 1, with a second and smaller hollow frustum of a cone open at its apex and base ends, supported coaxially with and within the first mentioned cone, the said smaller cone having its apex end extending in the same direction as the apex end of the first mentioned cone, the walls of the cones being separated a substantial distance, and slots formed through the walls of the two hollow cones and extending longitudinally thereof.

4. The combination with a loud speaker as set

forth in claim 1, with a second and smaller hollow frustum of a cone open at its apex and base ends, supported coaxially with and within the first mentioned cone, the said smaller cone having its apex end extending in the same direction as the apex end of the first mentioned cone, the walls of the cones being separated a substantial distance, and slots formed through the walls of the two hollow cones and extending longitudinally thereof, certain of the slots of the first mentioned cone being in line with slots of the smaller cone and other slots of the first mentioned cone being in line longitudinally of the cones with unslotted portions of the smaller cone.

5. A diffuser unit for deflecting sound waves of high frequency generated by a loud speaker, comprising a cylindrical open ended body adapted to be mounted at the front end of a speaker, a hollow frustum of a cone open at its base and apex ends mounted within said body in a manner to dispose the same in coaxial relation with and in front of the speaker cone with its apex end directed into the speaker cone, said first cone having a longitudinally convexed wall with openings therein for the coaxial passage of a portion of the high frequency waves therethrough, a second hollow frustum of a cone of materially less length and less overall diameter than the first mentioned cone, means supporting the second hollow cone coaxially within the first mentioned cone with its apex end extending in the same direction as the apex end of the first mentioned cone, the second mentioned hollow cone having its apex and base ends open, and said second hollow cone having openings in the wall thereof in alignment with the openings in the wall of the first mentioned cone whereby a proportion of the high frequency waves may pass through the two cones coaxially therewith, the said openings in the two hollow cones being in the form of relatively long slots extending longitudinally of the cones through substantially the full length thereof, and other slots formed longitudinally in the first mentioned one of the hollow cones adjacent to the apex end thereof and in line longitudinally of the cones with unslotted areas of the second mentioned cone.

6. A diffuser unit for deflecting sound waves of high frequency generated by a loud speaker, comprising a cylindrical open ended body adapted to be mounted at the front end of a speaker, a hollow frustum of a cone open at its base and apex ends mounted within said body in a manner to dispose the same in coaxial relation with and in front of the speaker cone with its apex end directed into the speaker cone, said first cone having a longitudinally convexed wall with openings therein for the coaxial passage of a portion of the high frequency waves therethrough, the deflector being provided with longitudinal slots through which a portion of the beam waves pass, and a second deflector formed to provide a straight deflecting surface disposed oblique to and in the path of certain of the beamed waves passing through the openings of the first deflector, said second deflector having openings in line with certain of the openings of the first deflector whereby certain of the beamed waves may pass therethrough.

7. A diffuser unit for deflecting sound waves of high frequency generated by a loud speaker, comprising a cylindrical open ended body adapted to be open at its base and apex ends mounted within said body in a manner to dispose the same in coaxial relation with and in front of the speak-

er cone with its apex end directed into the speaker cone, said first cone having a longitudinally convexed wall with openings therein for the coaxial passage of a portion of the high frequency waves therethrough, a second hollow frustum of a cone of materially less length and less overall diameter than the said first cone having its apex and base ends open, a spider supporting said second cone coaxially within said first cone, and said second cone having openings in the wall thereof in alignment with the openings in the wall of said first cone whereby a portion of the high frequency waves may pass coaxially through both of the cones and a portion thereof obliquely outward through said openings.
